MIXING MACHINE

James A. Davis, Topeka, Kans., assignor to
 Economy Building Block Machine Co., Inc.,
 Topeka, Kans., a corporation of Kansas

Application January 20, 1950, Serial No. 139,566

4 Claims. (Cl. 259—9)

1

My invention relates to a mixing machine.

A primary object of the invention is to provide a machine for thoroughly mixing soil with cement in any desired proportions.

A further important object is to provide a mixing machine including rotary, spring loaded means for crushing clods of soil and kneading and mixing the cement into the soil.

A further object is to provide a mixing machine of the above-mentioned character including a stationary drum and rotating scraper means arranged within the drum in trailing relation with respect to the mixing means, so that the soil and cement will be scraped from the drum after it is kneaded or pressed together by the mixing means.

A further object is to provide a soil and cement mixing machine of the above-mentioned character including a conveyor for introducing soil into a mixing drum in an even and continuous manner, the mixing drum being arranged so that the soil and cement pass through the same in an even and continuous manner under the influence of gravity and are discharged from one end of the mixing drum after the mixing operation is completed.

A further object is to provide novel rotating mixing and scraping mechanism for a mixing machine of the above-mentioned character.

A still further object of the invention is to provide a mixing machine of the above-mentioned character which is highly simplified, compact and extremely sturdy and durable, yet relatively light weight in construction.

Other objects and advantages of the invention will be apparent during the course of the following description.

In the accompanying drawings forming a part of this application, and in which like numerals are employed to designate like parts throughout the same:

Figure 1 is a side elevational view of a mixing machine embodying the invention, parts broken away;

Figure 2 is an end elevational view of the machine, parts broken away;

Figure 3 is a transverse, substantially vertical sectional view taken on line 3—3 of Figure 1; and

Figure 4 is a central, vertical, longitudinal sectional view taken on line 4—4 of Figure 2.

In the drawings, where, for the purpose of illustration, is shown a preferred embodiment of the invention, the numeral 10 designates generally a stand or support for the machine including pairs of upstanding, vertical posts or legs 11

2

and 12 rigidly connected at their bottoms by means of pairs of horizontal, longitudinal and transverse members or rails 13 and 14. The tops of the pairs of legs 11 and 12 are preferably disposed at substantially the same elevation.

Arranged adjacent to the tops of the pairs of legs 11 and 12 and between the pairs of legs is an elongated, longitudinally extending, slightly inclined, stationary mixing drum or shell 15, which is cylindrical, and which includes flat, upstanding end plates 16 and 17 integrally connected with the cylindrical side wall 18 of the drum. Near and longitudinally inwardly of the end of the drum which is disposed at the highest elevation, the drum is provided upon opposite sides with diametrically oppositely arranged, flat, vertical channel sections or plates 19 rigidly secured to the periphery of the drum by welding or the like. These plates 19 are disposed adjacent to the inner faces of the legs 12 and adjacent to the tops of such legs and arranged in sliding contact with the legs 12. The plates 19 are pivotally connected with the legs 12 by means of suitable pivot pins or bolts 20 extending through apertures formed in the tops of the legs 12 and in the plates 19. The upper or right-hand end of the drum, Figures 1 and 4, is thus pivotally mounted upon the tops of the legs 12, so that the drum 15 may have its inclination or slope adjusted by swinging it upon the pins or bolts 20. An additional pair of diametrically oppositely arranged, vertical plates or channel sections 21 are rigidly secured to the opposite sides of the drum 15 near its opposite or lower end, and the plates 21 are arranged adjacent to the inner faces of the pair of legs 11 and in sliding contact therewith. A pair of detachable clamp plates or channel sections 22 is provided adjacent to the plates 21 and disposed upon the outer sides of the legs 11, and the plates 21 and 22 are tightly clamped together with the legs 12 between them by means of clamping bolts 23 or the like. It is thus seen that the end of the drum 15 adjacent to the legs 11 may be raised and lowered and secured in the selected adjusted position by manipulating the bolts 23.

The stationary mixing drum 15 is provided in its bottom and adjacent to the end plate 16 with a large discharge opening 24. The drum is further provided in its top and adjacent to the opposite end plate 17 with an inlet opening 25 surrounded by a short, upstanding, tubular spout or sleeve 26 integrally connected with the top of the drum. A large top section 27 of the drum 15 is hingedly connected with the side wall 18

of the drum by means of a longitudinally extending hinge 28 which is spaced transversely upon one side of the longitudinal center line of the drum. The hinge 28 and top section 27 preferably extends for the entire length of the drum 15 and the section 27 constitutes an upwardly swingable, wide cover for the top of the drum, which may be opened to afford access to the interior of the drum. The top section or cover 27 preferably extends circumferentially about approximately one-quarter of the circumference of the drum, and the longitudinal edge 29 of the cover remote from the hinge 28 is preferably disposed near the vertical center of the drum. The top section or cover 27 has apertured lugs 30 rigidly secured to it, by welding or the like, and companion apertured lugs 31 are suitably rigidly secured to the side wall 18 below the lugs 30. Detachable bolts 32 are provided for detachably connecting the lugs 30 and 31 together, so that the cover 27 may be held firmly closed.

The end plates 16 and 17 of the drum are provided with axially aligned openings 33 and 34 for freely rotatably receiving a central, longitudinally extending drive shaft 35 which extends for the entire length of the drum 15 and axially outwardly of the end plates 16 and 17, as shown. The opposite ends of the drive shaft 35 are journaled in suitable bearings 36 and 37 rigidly secured to the outer faces of the end plates 16 and 17 and arranged in axial alignment. Inwardly of the bearing 36 a suitable packing ring or seal 38 is provided for sealing the opening 33 which is at the lowermost end of the drum. The end of the drive shaft 35 adjacent to the bearing 37 is provided with an integral, reduced, square extension 39 upon which is securely mounted for rotation with the drive shaft a sprocket member or hub 40 carrying inner and outer sprocket wheels 41 and 42 is securely mounted upon the square extension 39 for rotation with the drive shaft 35. The outer sprocket wheel 42 is preferably larger than the inner sprocket wheel 41, as shown. Both sprocket wheels are disposed close to the adjacent end plate 17 of the drum.

Rigidly mounted upon the drive shaft 35 within the drum 15 in any suitable manner, such as by welding, is an elongated housing such as a tube or sleeve 43 which is rectangular in transverse cross-section, Figure 3, and this sleeve extends for substantially the entire length of the drive shaft between the end plates 16 and 17. The tube or sleeve 43 rotates with the drive shaft and cannot move relative thereto. The sleeve or tube 43 includes opposed pairs of parallel, flat sides 44 and 45 which are arranged at right angles, Figure 3.

Pairs of longitudinally spaced, arcuate spring arms or supports 46 are disposed within the drum 15 and extend generally circumferentially therein. The spring arms 46 surround the tube 43 and are spaced radially therefrom and between the sleeve 43 and side wall 18 of the drum. The inner ends of the spring arms 46 are bent to provide generally radial, straight extensions or arms 47 bolted or otherwise rigidly secured to the adjacent flat sides 44 or 45. The free ends of the spring arms 46 which have their extensions secured to the pair of sides 45 are diametrically oppositely disposed, and the free ends of the spring arms 46 which have their extensions secured to the sides 44 are diametrically oppositely disposed, Figure 3. The spring arms 46 secured to the sides 45 of the tube 43

thus have their free ends spaced circumferentially 90° from the free ends of the spring arms 46 which are secured to the sides 44. The spring arms 46 are spring biased radially outwardly toward the side wall 18 of the drum 15. The spring arms 46 are preferably formed from heavy spring steel or the like, and the arms are quite stiff and exert a substantial force radially outwardly. The arrangement is such that the straight extensions 47 of the spring arms which are secured to the sides 45 are parallel and arranged at right angles to the extensions 47 of the spring arms which are secured to the sides 44. Arranged between the free ends of each pair of spring arms 46 is a large, cylindrical roller or wheel 48 having a hard, solid rubber tire 49 mounted thereon. Each roller 48 is freely rotatably mounted upon a short shaft or axle 50 having its opposite ends rigidly mounted within rings or loops 51 integrally formed upon the free ends of the pairs of spring arms 46. The rubber tired rollers 48 are thus bodily carried by the spring arms 46 and resiliently urged by the spring arms into rolling contact with the inner surface of the drum 15. Since the spring arms 46 are quite heavy and stiff, the rollers 48 will bear against the inner surface of the drum with considerable force. When the drive shaft 35 rotates, all of the spring arms 46 and rollers 48 turn with it, and the rollers revolve upon their shafts 50 and roll over the inner surface of the drum 15. As clearly shown in Figure 4, the circumferential and longitudinal spacing of the rollers 48 is such that substantially the entire inner surface of the stationary drum 15 is traversed by the rollers when the drive shaft 35 rotates. The rollers 48 need not be rubber tired, and if desired, the rollers may be formed of metal, or any other suitable material.

Pairs of straight, substantially radial, rigid arms or bars 52 are arranged in laterally spaced relation between each pair of spring arms 46, and the inner ends of the rigid arms 52 are bolted or otherwise rigidly secured to the adjacent flat sides 44 or 45 of the rectangular sleeve 43. The outer ends of the arms 52 terminate near the inwardly of the side wall 18, as shown. The arms 52 which are secured to the sides 45 are parallel and arranged at right angles to the arms which are secured to the sides 44. Each pair of arms 52 between each adjacent pair of spring arms 46 is secured to the same side 44 or 45 of the tube 43. All of the arms 52 are preferably slotted adjacent to their inner ends, so that the arms may be adjusted radially with respect to the side wall 18. All of the arms 52 are bent near their outer or free ends for forming short, inclined extensions or portions 53 which extend substantially truly radially with respect to the side wall 18. Elongated, straight scraper blades 54 are bolted or otherwise rigidly secured to the extensions 53, as shown, and the outer, longitudinal edges of the scraper blades are disposed in sliding contact with the inner surface of the side wall of the drum 15. The scraper blades 54 extend longitudinally or axially of the drum. The length of the scraper blades 54 are preferably equal to the axial length of the rollers 48, so that the scraper blades will scrape the same area or segment of the drum traversed by the roller 48 adjacent to the particular scraper blade. The arrangement is such that the scraper blades 54 carried by the arms 52 which are secured to the sides 45 follow or trail behind the rollers 48 carried by the spring arms 46 which are also secured to the

sides 45, Figure 3. Accordingly, the scraper blades carried by the arms 52 which are secured to the sides 44 trail behind the rollers 48 which are carried by the spring arms 46 secured to the sides 44. Each scraper blade 54 is accordingly spaced circumferentially substantially 90° from the roller 48 which it follows, and such scraper blade follows directly in the circumferential path of the roller with which it is associated. As viewed in Figure 3, the scraper blades 54 and rollers 48 move clockwise during the operation of the machine, so that the inclined radial extensions 53 and scraper blades 54 project forwardly with respect to the path of travel of the rotary mechanism within the stationary drum 15.

An elongated, longitudinally extending conveyor 55 extends adjacent to the top of the mixing drum 15 for the entire length of the drum and slightly beyond the end plate 16 thereof. This conveyor 55 comprises an elongated trough or casing 56 which is substantially U-shaped in transverse cross-section and open at its top. The trough 56 includes upstanding ends 57 and 58 having bearings or sleeves 59 and 60 rigidly mounted upon their outer faces by welding or the like, and the bearings 59 and 60 are arranged in axial alignment. The trough 56 is supported near its opposite ends and adjacent to the opposite ends of the drum 15 by means of pairs of legs 61 and 62, suitably rigidly secured thereto. The legs 61 and 62 extend below the bottom of the trough 56, as shown, and diverge below the bottom of the trough for straddling the top of the cylindrical drum 15. The bottom ends of the legs 61 are freely disposed, and terminate adjacent to the outer side of the hinge 28, as shown. A narrow, radially projecting strip or plate 63 is rigidly secured to the periphery of the side wall 18 near and circumferentially spaced slightly from the hinge 28, and this strip or plate extends longitudinally for the entire length of the drum 15. The bottoms of the legs 61 rest freely upon the side wall 18 of the drum, and also engage against the strip or plate 63 which serves as a stop or holder which prevents the legs 61 from sliding downwardly over the periphery of the drum 15. The legs 62 at the opposite side of the trough 56 have their bottom ends detachably connected with radially projecting apertured lugs 64 suitably rigidly secured to the cover 27 by means of bolts 65 or the like. The arrangement is such that when it is desired to raise the cover 27, the conveyor 55 may be bodily removed from the drum 15 by merely removing the bolts 65. The legs 61 and 62 maintain the bottom of the trough 56 spaced radially slightly above the top of the drum 15, Figure 3. The trough 56 is provided in its bottom and adjacent to the end 58 with a discharge opening 66 surrounded by a short, depending spout or sleeve 67 integrally secured to the trough and extending into the spout 26, as shown. Freely rotatably mounted within the U-shaped trough 56 and extending for substantially the entire length thereof is a screw type conveyor element or auger 68 including a radially projecting spiral vane 69 integrally secured thereto. At its opposite ends, the auger 68 is provided with reduced axle extensions 70 and 71 journaled within the bearings 59 and 60. The axle extension 71 projects axially beyond the bearing 60 and has rigidly secured to it for rotation therewith a sprocket wheel 72 disposed in lateral alignment with the inner sprocket wheel 41. A sprocket chain 73 is trained over the sprocket wheels 41 and 72, as shown.

A substantially horizontal motor stand or platform 74 is suitably rigidly mounted upon the side of the stationary drum 15 adjacent to the legs 62. This platform 74 is disposed adjacent to the end plate 17 of the drum, as shown. The platform 74 is arranged at an elevation somewhat below the drive shaft 35. A suitable gasoline engine 75 or the like is rigidly mounted upon the platform 74, and this engine includes a rotary power take-off shaft 76 connected with a suitable speed reducer 77 having a drive shaft 18 carrying a sprocket wheel 79. The sprocket wheel 79 is arranged in lateral alignment with the large sprocket wheel 42, and the sprocket wheel 79 is substantially smaller than the sprocket wheel 42. A second sprocket chain 80 is trained over the sprocket wheels 79 and 42 and extends substantially at right angles to the sprocket chain 73, Figure 2.

20 A longitudinally extending, horizontal platform 81 may be provided, and suitably rigidly mounted upon the legs 61. This platform is preferably disposed substantially at the elevation of the bottom of the drum 15, so that a worker may 25 stand upon it when the cover 27 is opened for gaining access to the interior of the drum 15. A worker standing upon the platform 81 may also view the inside of the trough 56.

The operation of the mixing machine is as 30 follows:

The engine 75 may be started for imparting rotation to the sprocket wheel 79, which, through the sprocket chain 80, will drive the sprocket wheel 42, in turn driving the shaft 35 clockwise, Figure 3. When this occurs, the sprocket chain 35 35 will be driven by the sprocket wheel 41 for driving the upper sprocket wheel 72, which in turn will impart rotation to the auger or conveyor screw 68. The auger 68 will also rotate 40 clockwise, Figure 3. With the drive shaft 35 thus rotating clockwise, Figure 3, the rollers 48 and scraper blades 54 will likewise travel clockwise about the interior of the stationary drum 15, as previously described.

45 With the mixing machine thus in operation, the properly proportioned amounts of soil and cement are introduced into the left-hand end of the trough 56, Figure 4, and the auger 68 will mix and convey these ingredients toward the right-hand end of the trough 56, where the ingredients may discharge through the opening 66 and into the top of the mixing drum 15. It should be mentioned that the left-hand or lower end of the mixing drum is previously vertically adjusted by 50 means of the bolts 23 and associated elements, to produce the desired inclination of the drum 15, so that the ingredients will gravitate toward the discharge opening 24 during the mixing operation.

The mixture of soil and cement will thus flow 55 into the mixing drum 15 through the discharge opening 66 in a continuous and even stream. Once within the drum 15, the ingredients will be acted upon by the mixing rollers 48 which are constantly rotating and rolling over the inner surface of the drum 15, as previously described. The mixture of soil and cement passes beneath the hard rubber tires of the rollers 48, and the rollers thoroughly knead and mix together the soil and cement, while crushing any large clods 60 of soil which may be present. When the soil is introduced into the trough 56, it may contain gravel or other hard substances which will be fed, together with the soil and cement, into the drum 15. When this gravel or hard substance 65 passes beneath the rollers 48, such rollers may

yield radially inwardly by virtue of their connection with the spring arms 46. The rollers 48 thus do not crush the gravel, but permit it to pass through the machine. The scraper blades 54 travel behind their associated rollers 48 to scrape the mixture of soil and cement from the inner surface of the drum 15 after the rollers have thoroughly mixed and kneaded the mixture against the side walls of the drum. As this mixing and scraping operation continues, the ingredients within the drum 15 gradually gravitate toward the end plate 16, and eventually discharge through the opening 24 in a continuous and even stream. A sufficient number of the rollers and scrapers are provided within the drum 15 to thoroughly mix the ingredients together, and in this connection it should be understood that any desired number of the rollers and scrapers may be provided, and I do not wish to limit the invention to the precise number of scrapers and rollers shown in the drawings.

A conventional type hammer mill or pulverizing machine, not shown, may be arranged beneath the discharge opening 24 for receiving the mixed soil and cement together with any gravel which may be present, as these ingredients pass through the discharge opening 24. The hammer mill or pulverizer will thoroughly pulverize the mixture which is discharged from the mixing machine, so that the resultant product will be ready for use in making building blocks or the like. The hammer mill need not completely pulverize the mixture discharged from the opening 24. Its use is mainly to break up cakes or clods of the mixture formed by the rollers 48, so that mixed material will be better adapted to be measured for forming building blocks of uniform weight and size.

The rate of travel of the ingredients through the drum 15 may be varied by raising and lowering the left-hand end of the drum, Figure 4, as previously stated. By thus increasing the rate of flow or travel of the ingredients through the mixing drum 15, the number of times which the ingredients will pass beneath the rollers 48 will also be varied.

Obviously, the mixing machine may be employed for mixing various types of ingredients, and I do not wish to limit the invention to its use for mixing soil and cement only. If desired, the entire machine may be mounted upon a suitable trailer for mobility. The construction of the machine is highly simplified, compact and extremely sturdy. Due to the rolling action of the rollers 48, and the absence of any hammering or impact producing elements, the machine will have an extremely long life in use.

It is to be understood that the form of the invention herewith shown and described is to be taken as a preferred example of the same, and that various changes in shape, size and arrangement of parts may be resorted to without departing from the spirit of the invention or the scope of the subjoined claims.

Having thus described my invention, I claim:

1. A mixing machine comprising a base, a closed drum arranged longitudinally of said base and mounted on said base for movement from a horizontal position to a position at an angle with respect to the horizontal, a longitudinally extending shaft positioned within said drum and rotatably supported thereon, one end of said shaft projecting out of said drum, a longitudinally extending housing circumscribed about said shaft and fixedly secured thereto, a plurality of transversely disposed spring supports positioned in

staggered spaced relation about and along said housing and each having one end secured to the latter, a longitudinally disposed roller rotatably supported in the other end of each of said supports and engageable with the inner surface of said drum, the respective rollers being of a length such that the rotative paths of travel of longitudinally adjacent rollers partially overlap each other, said drum being provided with an inlet for the introduction of the material to be mixed and an outlet for the discharge of the mixed material, and means operatively connected to the projecting end of said shaft for effecting rotation of said shaft.

2. A mixing machine comprising a base, a closed drum arranged longitudinally of said base and mounted on said base for movement from a horizontal position to a position at an angle with respect to the horizontal, a longitudinally extending shaft positioned within said drum and rotatably supported thereon, one end of said shaft projecting out of said drum, a longitudinally extending housing circumscribed about said shaft and fixedly secured thereto, a plurality of transversely disposed spring supports positioned in staggered spaced relation about and along said housing and each having one end secured to the latter, a longitudinally disposed roller rotatably supported in the other end of each of said supports and engageable with the inner surface of said drum, the respective rollers being of a length such that the rotative paths of travel of longitudinally adjacent rollers partially overlap each other, said drum being provided with an inlet for the introduction of the material to be mixed and an outlet for the discharge of the mixed material, and means operatively connected to the projecting end of said shaft for effecting rotation of said shaft.

3. A mixing machine comprising a base, a closed drum arranged longitudinally of said base and mounted on said base for movement from a horizontal position to a position at an angle with respect to the horizontal, a longitudinally extending shaft positioned within said drum and rotatably supported thereon, one end of said shaft projecting out of said drum, a longitudinally extending housing circumscribed about said shaft and fixedly secured thereto, a plurality of transversely disposed spring supports positioned in staggered spaced relation about and along said housing and each having one end secured to the latter, a longitudinally disposed roller rotatably supported in the other end of each of said supports and engageable with the inner surface of said drum, the respective rollers being of a length such that the rotative paths of travel of longitudinally adjacent rollers partially overlap each other, each of the spring supports embodying a pair of leaf springs arranged in parallel spaced relation and each having one end fixedly secured to the housing, a longitudinally disposed roller rotatably supported in the other end of each of said pairs of leaf springs, said drum being provided with an inlet for the introduction of the material to be mixed and an outlet for the discharge of the mixed material, and means operatively connected to the projecting end of said shaft for effecting rotation of said shaft.

4. A mixing machine comprising a base, a

closed drum arranged longitudinally of said base and mounted on said base for movement from a horizontal position to a position at an angle with respect to the horizontal, a longitudinally extending shaft positioned within said drum and rotatably supported thereon, one end of said shaft projecting out of said drum, a longitudinally extending housing circumscribed about said shaft and fixedly secured thereto, a plurality of transversely disposed spring supports positioned in a staggered spaced relation about and along said housing and each having one end secured to the latter, a longitudinally disposed roller rotatably supported in the other end of each of said supports and engageable with the inner surface of said drum, the respective rollers being of a length such that the rotative paths of travel of longitudinally adjacent rollers partially overlap each other, each of the spring supports embodying a pair of leaf springs arranged in parallel spaced relation and each having one end fixedly secured to the housing, a longitudinally disposed roller rotatably supported in the other end of each of said pairs of leaf springs, a plurality of transversely disposed scrapers positioned exteriorly of and carried by said housing and each engageable with the inner face of said drum, said scrapers

being arranged so that a scraper is in back of and spaced from one of the adjacent rollers, said drum being provided with an inlet for the introduction of the material to be mixed and an outlet for the discharge of the mixed material, and means operatively connected to the projecting end of said shaft for effecting rotation of said shaft.
